DESIGN FOR A HAIR CURLER

Orlando E. Izquierdo, Habana, Cuba

Application July 25, 1939, Serial No. 86,236

Term of patent 14 years

To all whom it may concern:

Be it known that I, Orlando E. Izquierdo, a citizen of Cuba, residing at Habana, Cuba, have invented a new, original, and ornamental Design for a Hair Curler, of which the following is a specification, reference being had to the accompanying drawing, forming part thereof wherein:

I claim:

The ornamental design for a hair curler, as shown.

ORLANDO E. IZQUIERDO.
